Primary Examiner — Bao-Yen T Nguyen

Assistant Examiner — Emily Anna Saunders

(57) **CLAIM**

The ornamental design for a playing card holder, as shown and described.

DESCRIPTION

FIG. 1 is a front, right side and top perspective view of the playing card holder showing my new design.

FIG. 2 is a rear, left side, bottom perspective view thereof.

FIG. 3 is a front view thereof.

FIG. 4 is a rear view thereof.

FIG. 5 is a left side view thereof.

FIG. 6 is a right side view thereof.

FIG. 7 is a top view thereof.

FIG. 8 is a bottom view thereof; and,

FIG. 9 is a bottom perspective view of the playing card holder, in an alternate configuration.

The broken lines in the drawings illustrate portions of the playing card holder that form no part of the claimed design.

1 Claim, 9 Drawing Sheets
